US0D1102462S

(12) **United States Design Patent** (10) Patent No.: **US D1,102,462 S**
Woudhuysen et al. (45) Date of Patent: ** Nov. 18, 2025

(54) **DISPLAY SCREEN OR A PORTION THEREOF WITH A GRAPHICAL USER INTERFACE**

(71) Applicant: **IGT**, Las Vegas, NV (US)

(72) Inventors: **Brandon Woudhuysen**, Sparks, NV (US); **Rebecca Schwalm**, Egg Harbor Township, NJ (US); **Eric Loat**, Carson City, NV (US)

(73) Assignee: **IGT**, Las Vegas, NV (US)

(**) Term: **15 Years**

(21) Appl. No.: **29/966,476**

(22) Filed: **Oct. 2, 2024**

(51) LOC (15) Cl. **14-04**

(52) U.S. Cl.

USPC **D14/485**; D14/490; D14/492

(58) **Field of Classification Search**

CPC .. G07F 17/34; G07F 17/3211; G07F 17/3213; G07F 17/3267

See application file for complete search history.

(57) **CLAIM**

The ornamental design for a display screen or a portion thereof with a graphical user interface as shown and described.

DESCRIPTION

The FIGURE is a front view of a display screen or a portion thereof with a graphical user interface, showing our new design.

The dashed broken line perimeter in the drawings illustrate a display screen or a portion thereof and forms no part of the claimed design. The remaining dashed broken lines in the drawings illustrate portions of the graphical user interface that form no part of the claimed design.

1 Claim, 1 Drawing Sheet
